(57) CLAIM

The ornamental design for a game bag, as shown and described.

DESCRIPTION

FIG. 1 is a perspective view of a game bag showing the claimed design.

FIG. 2 is a front view thereof.

FIG. 3 is a rear view thereof.

FIG. 4 is a left-side view thereof.

FIG. 5 is a right-side view thereof.

FIG. 6 is a bottom view thereof; and,

FIG. 7 is a top view thereof.

Broken lines in the figures show portions of the game bag that form no part of the claimed design.
